UNITED STATES PATENT OFFICE.

HENRY W. ANSELL, OF STAGI, SWAZILAND, SOUTH AFRICA.

DESIGN FOR A SHAVING-STICK HOLDER.

Application filed January 27, 1927. Serial No. 20,518. Term of patent 3½ years.

To all whom it may concern:

Be it known that I, HENRY W. ANSELL, a subject of the King of Great Britain, residing at Stagi, Swaziland, South Africa, have invented a new, original, and ornamental Design for a Shaving-Stick Holder, of which the following is a specification, reference being had to the accompanying drawing, forming a part thereof.

The design comprehends a shaving stick holder having a general frusto-conical shape with flat faces extending from the extreme

lower edge thereof to a point short of the top and terminating in an annular bead which extends beyond said faces.

Figure 1 is a side elevation of the shaving stick holder, showing my new design,

Figure 2 is a top plan view thereof, and

Figure 3 is a longitudinal section through the same.

I claim:

The ornamental design for a shaving stick holder, as shown and described.

HENRY W. ANSELL.
